SHOE FORM

Paul W. Senfleben, Malden, Mass., assignor to
United Shoe Machinery Corporation, Flemington, N. J., a corporation of New Jersey.

Application October 31, 1947, Serial No. 783,293

5 Claims. (Cl. 12—124)

1

The purpose of the present invention is to provide a shoe-making last capable of being extended and shortened for shoes of different lengths, and capable also of affording relative angular movement of the forepart and heel part with each length adjustment of the last.

A feature of the invention is embodied in adjustable means connecting the forepart and the heel part and including two interlocking members so formed as to provide pivotal connection and length adjustments without permitting the forepart and heel part to be uncoupled.

A last embodying this feature is illustrated herein as designed to serve the purposes of a plurality of lasts in a machine of the type set forth in my application for United States Letters Patent Serial No. 694,965, filed September 5, 1946.

Referring to the accompanying drawings,

Fig. 1 represents a side elevation of a last embodying the invention and adjusted to its shorter length;

Fig. 2 represents the same last adjusted to its longer length;

Fig. 3 is a magnified perspective view representing the pivot member and a fragment of the slotted tongue with which it cooperates;

Fig. 4 is a horizontal section through the parts connected by the pivot member; and

Fig. 5 is an elevation of the slotted portion of the tongue.

The last represented in the drawings is not one of the more common types on which uppers are lasted. It is made entirely of metal and comprises a forepart 10, a heel part 11, a flat tongue 12 rigidly related to the heel part, and a pivot member including two cylindrical bearing portions 14 and 15 and a smaller portion 16 connecting them. The tongue 12 extends into a heightwise cleft between two spaced cheeks 13, 13 into which the rear end of the forepart is divided, and the lapped portions of the tongue and the cheeks are connected by the pivot member.

A bore extends widthwise through the cheeks 13, 13 to provide bearings for the bearing portions 14 and 15, respectively, and a slot 17 formed in the tongue 12 is occupied by the smaller portion 16 of the pivot member. The slot provides for changing the effective length of the last, and the pivot member permits relative angular movement of the forepart and heel part consistent with clearances provided by a notch 18 in the heel part and a notch 19 in the tongue.

One face of the tongue 12 is provided with a circular recess 21, and the opposite face is provided with a circular recess 22. The pivot mem-

2

ber may be shifted lengthwise of its axis to seat the bearing portion 14 in the recess 21 or the bearing portion 15 in the recess 22, as the case may be, but these circular recesses are out of register with each other. Nevertheless, when the last is adjusted for shorter length (Fig. 1) the recess 22 will be in register with the bearing portion 15, and the latter may be shifted into it or out of it. Likewise, when the last is adjusted for longer length (Fig. 2) the recess 21 will be in register with the bearing portion 14, and the latter may be shifted into or out of it. Accordingly, the recesses and the pivot member provide separable interlocking surfaces outside the slot 17 by which various pivotal relations of the tongue and the forepart may be established.

The bearing portions 14 and 15 are spaced one from the other by a distance slightly greater than the thickness of the tongue 12 to permit adjusting the last for length when the pivot member lies in a position midway between its limits of endwise movement. A detent is provided to maintain the pivot member in either of the positions in which one of its bearing portions will be seated in one of the circular recesses. The detent includes a steel ball 23, a compression spring 24 and a screw-plug 25, all nested in a socket 26 in the forepart. The ball engages the bearing portion 14 in which two retaining grooves 27 and 28 are formed and arranged to be moved alternatively into register with the ball. Moderate finger pressure against the ends of the pivot member is sufficient to shift it despite the resistance of the detent.

The slot 17 is narrower than the bearing portions 14 and 15, but not so narrow as the connecting portion 16. Consequently, although the portions 14 and 15 cannot pass through the slot and so permit detaching the forepart and heel part from each other, they serve alternatively to sustain the stresses to which a last is subjected. The comparatively slender connecting portion 16, on the other hand, is relieved of all stresses except those of shifting the bearing portions 14 and 15 endwise.

When a last of this type is used for the purposes set forth in my aforesaid application Serial No. 694,965 it may be mounted on a stand 30 (broken lines in Fig. 1) having provisions for quickly interchanging lasts. The stand 30 is made of flat metal of the same thickness as the tongue 12. The heel part, as well as the forepart, has a cleft, the cleft in the heel part being bridged by two pins 31 and 32. Two notches 33 and 34 are formed in the member 30 and are so arranged that if the pin 31 is placed first in the notch 33

with the toe of the last pointed upwardly, the pin 32 will enter the notch 34 in consequence of rocking the last on the pin 31. The lower edge of the tongue 12 may thus be seated on the upper edge of the stand 30, as indicated in Fig. 1.

Having described my invention, what I claim as new and desire to secure by Letters Patent of the United States is:

1. A last comprising a forepart having a height-wise cleft in its rear end, an individual heel part having a tongue rigidly related thereto and extending into said cleft, and a pivot member having two spaced bearing portions and a smaller portion connecting them, said tongue having a slot narrower than said bearing portions through which said smaller portion extends, and the forepart having a bore in which said bearing portions are seated.

2. A last comprising a forepart having a height-wise cleft in its rear end, an individual heel part having a tongue rigidly related thereto and extending into said cleft, and a pivot member having two spaced cylindrical bearing portions and a smaller portion connecting them, said tongue having a slot narrower than said bearing portions through which said smaller portion extends, said tongue also having a circular recess into and out of which one of said bearing portions may be shifted by moving the pivot member endwise, and the forepart having a bore in which said bearing portions are seated and slidable.

3. A last comprising a forepart having a height-wise cleft in its rear end, an individual heel part having a tongue rigidly related thereto and extending into said cleft, and a pivot member having two spaced cylindrical bearing portions and a smaller portion connecting them, said tongue having non-registering circular recesses in its opposite faces and a slot intersecting them, said

smaller portion extending through said slot and said bearing portions being movable into and out of said recesses respectively, and the forepart having a bore in which said bearing portions are seated and slidable.

4. A last comprising a forepart having a height-wise cleft in its rear end, an individual heel part having a tongue rigidly related thereto and extending into said cleft, a pivot member having two cylindrical bearing portions spaced apart and connected by a smaller portion, said tongue having a slot narrower than said bearing portions through which said smaller portion extends, the tongue also having a circular recess in one face to receive one of said bearing portions and another circular recess in the opposite face to receive the other one of said bearing portions, the forepart having a bore in which said bearing portions are seated and slidable, and means arranged to maintain said pivot member in either of two operative positions.

5. A last comprising a forepart having a height-wise cleft in its rear end, an individual heel part having a tongue rigidly related thereto and extending into said cleft, and a pivot member movable endwise in the forepart and connecting said tongue and the forepart, said tongue having a slot through which the pivot member extends and by which the forepart and heel part are rendered movable one toward and from the other to vary the length of the last, the tongue and said pivot member having separable interlocking surfaces outside said slot by which various pivotal relations of the tongue and the forepart may be established.
